FIG. 5.

FIG. 6.

Inventor:

Charles L. Russell

UNITED STATES PATENT OFFICE.

CHARLES LYON RUSSELL, OF NEW YORK, N. Y.

DRILL-CHUCK.

1,351,347.

Specification of Letters Patent. Patented Aug. 31, 1920.

Application filed December 6, 1918. Serial No. 265,629.

To all whom it may concern:

Be it known that I, CHARLES LYON RUSSELL, a citizen of the United States of America, residing at the city of New York, in the 5 county of Bronx, State of New York, have invented certain new and useful Improvements in Drill-Chucks, of which the annexed is a specification, reference being had to the accompanying drawings.

10 This invention relates more particularly to automatic drill chucks, and has for an object to provide in such a chuck of the rolling jaw type, a wide range of jaw opening, a strong gripping action and a form of jaw 15 affording many manufacturing advantages.

In the drawings accompanying this specification one practicable embodiment of my invention is shown by way of illustration, wherein:

20 Figure 1 is a side elevation, partly in central section of my improved chuck.

Fig. 2 is an elevation of the body portion which carries the jaws.

Fig. 3 is a cross sectional view, taken at 25 about the plane of the line 3—3 of Fig. 1.

Fig. 4 is a similar cross sectional view, showing the jaws in their closed position.

Fig. 5 is a cross sectional view, taken on a plane at about the line 5—5 of Fig. 1.

30 Fig. 6 is an enlarged fragment of the showing of Fig. 4, and

Fig. 7 is a perspective view of one of the jaws removed from chuck.

The body portion 8 of the chuck, illustrated in elevation in Fig. 2, is that portion which may be regarded as carrying the jaws and which is adapted to be connected to the rotary driving spindle in some suitable manner, preferably by a taper seat, illustrated

35 by the dotted lines 9. This present chuck is an improvement on that style of chuck, wherein cylindrical jaws are forced inwardly by means of cams and into position to engage the drill spindle, whereupon the

40 45 combined action of the parts effects a rolling motion of the jaws and forces them by a rolling motion farther up on the cam surfaces and consequently inwardly and against the drill shank. In the present instance

50 55 there are shown three jaws 10, each of these jaws being a segment of a cylinder, preferably a truncated cylinder wherein the bases are of substantially equal area. In the manufacture of these jaws an easy procedure is to turn up the cylinders or rather a

long bar into the proper cylindrical shape and slab off the sides 11. By this means, the curved portions 12 will be true cylinders and the portion of the rolling face 12, adjacent the side 11, will remain intact, which condition would be hard to accomplish if a flat bar were placed in a grinding machine and its edges ground to cylindrical form.

60 A sleeve 13 is shown surrounding the major portion of the head 8 and carrying fast with it a cam member 14. This cam member may be constructed on a broaching machine and have the sleeve shrunk on it, whereby the two parts are rigidly connected together.

65 70 75 A cam 15 is provided for each jaw. The head is provided with a slot 16 for each jaw. The side walls of the slots are preferably so located that a plane midway between them is disposed substantially radially of the head 8. These side walls 17 are located a sufficient distance apart in relation to the thickness of the rollers, that is the distance apart of the faces 11, that the jaws may have a rocking movement in the slots. Some 80 85 convenient means may be employed for holding the jaws in their initial or idle position. In the present illustration the jaw is shown carrying at the top and bottom of each side, a spring finger 18. The fingers on the forward side being directed inwardly and engaging the side of the slot toward the center of the head, and those on the rear side engaging the outer edge of the slot, thereby normally holding the jaws in a position opposite to that shown in Fig. 6. To enable the spring fingers to escape crushing, suitable recesses 19 are provided in the jaws for receiving these fingers when depressed.

90 95 100 In the operation of this form of automatic drill chuck, the jaws are normally held at their extreme inward or closed position. This is usually effected by spring means. In the present illustration, a coiled clock spring 20 is shown connected to the head 8 and to the sleeve 13, in such manner that these parts are rotated one relatively to the other and into such a position that the jaws normally occupy a position at the crests 21 of the cams. When it is desired to 105 insert a tool spindle into the center bore of the head and through the opening 22 in the sleeve, the operator grasps the chuck, which is assumed to be rotating, that is he grasps the sleeve 13 and permits it to slide fric- 110

tionally in his hand, this compresses the spring 20 and causes a relative rotation of the sleeve and body which brings them into approximately the Fig. 3 position, so that 5 upon the insertion of the tool shank 23 the jaws will be pressed outwardly a sufficient amount to receive the tool shank and may, if desired, be pushed outwardly to the full extent of their outward movement and until 10 they engage the low portion 24 of the cams. In the Fig. 3 position, it will be seen that owing to the slabbing off of the sides of the cylindrical jaw, the jaw has a greater amplitude of movement across the face of the 15 cam and consequently a greater movement radially of the chuck body than is possible with a full cylinder. Upon the operator releasing the sleeve 13 to the action of the spring 20, the relative movement of the body 20 8 and sleeve 13 with the cams 14, causes the jaws to move inwardly until they engage the tool shank 23. The jaws slide upon the cams as they are carried forwardly thereon, and as soon as the inward rounded edges of the 25 jaws are pressed against the tool shank, by their inward movement, a rolling motion is given the jaws and they roll against the tool shank and roll forwardly on the cam, thereby increasing the grip upon the tool shank 30 in excess of the bite which is effected by an inward radial movement of the jaw unaccompanied by this rolling movement. Owing to the fact that there is a true rolling motion between the jaw and the cam, 35 and the jaw and the tool shank, none of the

three parts named is injured or marred by the strong clamping engagement afforded.

Although but one illustrative embodiment of the invention has been shown and described, it will be apparent that changes 40 will be made within the scope of the claims without departing from the spirit of my invention.

What I claim as my invention is:—

1. In a chuck, the combination with a 45 sleeve, of a jaw carrier mounted in and rotatable relatively to said sleeve, the jaw carrier having a centrally disposed tool seat and jaw pockets extending outwardly from such tool seat, and a substantially flat jaw 50 in each such pocket having a rounded tool engaging face at its inner edge and a rounded cam engaging face at its outer edge, the sleeve being provided on its inner face with jaw engaging cams, the width of the jaw 55 pockets and the width of the jaws being of such relative proportions that the jaw has a loose fit in the pocket and is capable of inward edgewise movement by the action of the cam and is also capable of a limited 60 rolling movement against the cam and against the tool when the said rounded edge faces are engaged by these.

2. A chuck as set forth in claim 1 wherein the rounded edges of the jaw are substantially cylindrical segments having a common axis.

In testimony whereof I affix my signature this 27th day of November, 1918.

CHARLES LYON RUSSELL.
